PASTE APPLYING MECHANISM

Wallace D. Kimball, Jackson Heights, N. Y., assignor to Standard-Knapp Corporation, Long Island City, N. Y., a corporation of New York

Application August 20, 1932, Serial No. 629,569

8 Claims. (Cl. 91—54)

This invention relates to mechanism for applying paste, glue or other adhesive to strips or the like, such, for example, as labels, to aid in securing them to articles such as cans, bottles and similar containers.

Difficulty has heretofore been experienced in placing upon the strip or label just the right amount of paste to produce a good joint and in controlling the application of the paste so as to prevent it from spreading over an undesirably large area, or reaching parts of the label which should be kept free from paste.

The labeling machines by means of which the labels are applied to the articles are usually arranged to receive the ungummed labels in a stack containing from several hundred to a thousand or more labels. The labels lie in the stack upside down so that the back of the uppermost label is exposed. They are removed one by one from the top of the stack by suitable mechanism which places them upon the articles. Paste is applied to the uppermost label just before it is removed from the stack.

The primary object of my present invention is to provide a mechanism which will apply the paste where it is desired without getting too much paste on the label and without having it spread over an unduly large surface of the label, and also without having it run down the edges of the stack of labels thereby sticking them together.

Another object of the invention is to apply the paste in such a way as to avoid pulling the stack of labels over to one side, thereby moving them out of position to be properly acted upon by the mechanism for placing them on the articles.

The natural shape which labels of different kinds assume in a stack varies. Some labels remain perfectly straight, others bulge upwardly so that the paste is applied to a plane or convex surface. Sometimes, however, due to the printing or embossing on the front of the labels, they tend to present in the stack an upwardly concave surface. It is difficult to properly apply the paste to a concave label, and another object of the invention is to provide mechanism which will accomplish this and which can be readily adjusted to apply the paste to labels having any of these characteristics.

A further object of the invention is to provide a paste applying mechanism by which the amount of paste deposited upon the labels can be readily controlled or regulated.

The invention will be described in connection with a mechanism which has been provided for

use in connection with a machine for applying labels on round cans. Only a sufficient portion of the label applying machine will be illustrated, however, to show the general principle of operation of the label applying machine, and it will be understood that the device of my invention can be utilized wherever it is desired to apply a relatively narrow elongated band of paste across a flat, convex or concave surface.

The embodiment of my invention in a can labeling machine is shown in the accompanying drawings, wherein

Fig. 1 is a side elevation of the paste applying mechanism with certain parts shown in section, the entire view being also a section taken transversely and vertically of the labeling machine and through the stack of labels on the broken line 1—1 of Fig. 3;

Fig. 2 is a fragmentary and somewhat diagrammatic longitudinal section through a part of the labeling machine and the stack of labels, the section being taken on line 2—2 of Fig. 1;

Fig. 3 is a plan view of the paste-applying mechanism and the rear portion of the label stack and the parts adjacent thereto;

Fig. 4 is an enlarged transverse sectional view taken on line 4—4 of Fig. 3, showing the construction and relation of the parts which apply the paste to the uppermost label of the stack;

Fig. 5 is a detail sectional view taken on line 5—5 of Fig. 3;

Fig. 6 is a similar view taken on line 6—6 of Fig. 1;

Fig. 7 is a bottom view of one member of the mechanism;

Fig. 8 is a transverse section taken on broken line 8—8 of Fig. 3.

Referring now to the accompanying drawings, and first to Fig. 2, the cans, one of which is indicated at 1, advance through the labeling machine from left to right along the track 2, being propelled by the rolling action of the lower reach 3 of a continuously moving belt which is held in frictional contact with the upper sides of the cans by means of stationary guides or rollers 4.

Before reaching the position shown in Fig. 2, the can 1 is passed in contact with a plurality of rotating discs 5 which are mounted upon shaft 6 and which rotate within a body of glue or gum 7 and apply to the side of the can a plurality of spots of adhesive arranged in spaced relation throughout the length of the can.

The stack of labels 8 shown in longitudinal vertical section in Fig. 2 is placed at such a distance from the glue applying discs 5 that the can will

make one complete revolution in moving from the discs to the front end of the label stack, so that the spots of adhesive which have been applied to the can will pick up the front end of the uppermost label and stick it to the can. Then the can rolls up the inclined portions 9 of a pair of rails 10. This elevates the can above the top of the stack of labels and separates the uppermost label from the remainder of the stack.

10 The labels are of such length as to completely surround the can 1, and permit the ends of the labels to overlap one another. The label is held upon the can by the spots of glue applied to the front end of the label, and also by the narrow strip of paste which is applied by means of a belt 11 to the overlapping portion of the rear end of the uppermost label.

20 As the can 1 continues to advance along the elevated rails 10, the uppermost label is drawn to the left so that the right-hand or rear end of the label slides out from beneath the belt 11 and the belt then contacts with the next label. During this movement of withdrawal, the label slides beneath a curling bar 12, preferably having teeth 13, which yieldingly presses against the top of the 25 stack of labels.

30 Further rolling of the can along the rails 10 withdraws the label from beneath the curling bar 12 and completes the wrapping of the label about the can. Then the can rolls for a short distance 35 over a mat 14 which extends between the rails 10 and by which the weight of the can as it rolls along is caused to smooth out the label upon its surface, removing wrinkles, pressing together the overlapping ends of the label and leaving the label neatly applied.

35 The mounting for curling bar 12 consists of two bell cranks 15 pivoted at 16 to arms 17 which extend obliquely from brackets 17a and 17b, as 40 may be seen from Figs. 2 and 3. Helical springs 18 attached to bell cranks 15 yieldably urge the curling bar against the uppermost label. The complete description of brackets 17a and 17b will be found below.

45 By means of the improved belt which is included in my present invention, only a thin film of paste of pencil line width is applied to the label. This is spread out into a still thinner film by the belt itself as the strip slides out from beneath 50 the belt. In this way the paste is prevented from collecting on the curling bar, and then being rubbed off by the curling bar onto succeeding labels. Heretofore much difficulty has been experienced through the smearing of paste upon the 55 labels in this way, for wherever the paper adheres to the can between the ends of the label, it either rusts the can or wrinkles the label, depending upon atmospheric conditions.

60 The endless belt 11, by means of which the line of paste is applied to the surface of the uppermost label at the right-hand end, consists of a closely coiled helix of metal wire. This may be made of any suitable resilient material such, for example, as brass, copper, phosphor-bronze or steel. A belt 65 made of the hard steel wire known as "piano wire" has been found to give very satisfactory results. Belt 11 passes around the grooved driving pulley 19 mounted above a paste receptacle 20 at the left-hand side of the machine, as shown in Figs. 70 1 and 3. Pulley 19 is mounted upon shaft 21 and is rotated in the direction of the arrow shown in Fig. 1 so that the upper reach of the belt 11 moves to the right-hand side of the machine, passing beneath the end of mat 14 and around a stationary 75 guide member 22. The lower reach of the belt

then passes over a stationary guiding stud 23 and beneath a positioning shoe 24 by means of which the belt is delivered into contact with the surface of the uppermost label in the stack of labels 8. The belt passes across the label from one side edge to the other, beneath a yieldingly mounted arm 25, and then over a guide wheel 26 and back to driving pulley 19.

5 A body of paste 27 is contained within the paste receptacle 20 and rotating in this paste is a disc 10 28. This disc rotates continuously and throws a surplus of the paste against the pulley 19 so that the lower portion of this pulley and the belt 19 are continuously bathed in the paste. This surplus of paste is wiped off from both sides of the pulley, 15 the periphery of the pulley, and the belt 11, by means of a wiping device 29.

20 The body of wiping device 29 is provided with two side members or cheeks 30 which closely engage the sides of the pulley 19, and with an adjustable scraper 31, the end of which is grooved to receive the belt 11 and which closely fits the pulley and the belt. This scraper is adjusted into close rubbing contact with the belt and the edge of the pulley by means of two adjusting screws 32 and 25 then secured in this position by means of screw 33 which passes through a slot in the scraper and is threaded into the body of the wiping device. The wiping device 29 as a whole is secured to a short shaft 34 which is mounted in a bracket 35 30 and has attached at its opposite end an arm 36 to which a helical spring 37 is secured. The lower end of this spring is fixed to the frame of the machine.

35 By means of this construction the wiping device 29 is urged against the pulley 19 and belt 11 by means of the spring 37. An adjustable stop screw 38 is arranged to take a portion of the pressure of spring 37 and enables the scraper 31 to be resiliently but firmly held in extremely close rubbing engagement with the surface of the pulley and the belt without causing an undue amount of friction between the rubbing surfaces. In other words, this construction enables the employment of a reasonably heavy spring 37 so as to enable the scraper to effectively remove the large surplus of paste from the pulley and belt, and at the same time part of the stress of this spring is taken by the stop screw 38 instead of all of the stress being taken by the pulley.

50 The wiping device 29 is so adjusted that all of the paste applied to the belt 11 by means of disc 28 is removed except the paste which is retained by the capillarity of the spaces between the convolutions of the belt which have been indicated at 55 39 in the magnified view Fig. 4. When a metal belt having capillary spaces of this kind is passed over a curved stationary surface such as is formed on each of the projections 40 of the stationary guide 22, or a curved stationary surface such as 60 that of the guide stud 23, paste does not collect upon such surfaces to any substantial extent. It will be understood that instead of employing the stationary guide 22 and guide stud 23, pulleys or rollers may be used. If pulleys or rollers are employed, however, there is a tendency for the paste to accumulate on them and be thrown off. By utilizing the rounded-surfaced stationary guides no difficulty is experienced with the throwing or dripping of paste. A film of paste is applied by 65 the belt to the surfaces of the rounded guides, and this serves as a lubricant, but there is no collection of paste upon the guides. If paste is deposited from the interstices of the belt onto such a guide surface as the belt makes contact with the guide, 70 75 75

an equal amount of paste is removed by the interstices of the belt as the belt leaves the guide. Stationary guide member 22 is made in approximately semi-circular form and is provided with a sufficient number of spaced guide projections 40 to adequately support the belt 11 and cause it to bend in a sufficiently large radius of curvature to avoid sharp bends. Stationary guide member 22 is mounted with the plane of the centers of its projections 40 at a slight angle to the vertical so as to throw the lower reach of the belt 11 slightly ahead of the end of the mat 14 and the upper reach of the belt under the end of mat 14 so as to protect the same from contact with the label which is being wrapped about the can. This prevents the removal of adhesive from the upper reach of the belt and also prevents the smearing of the label with adhesive. Stationary guide member 22 is carried upon a block 41 which is slidably mounted upon a rigid bar 42 that extends crosswise of the labeling machine from a bracket 43 on the adhesive receptacle 20. Bar 42 is firmly and adjustably secured to this bracket by means of a wing nut 44.

The slideable block 41 upon which guide member 22 is carried is held in position by means of a hand screw 45 which passes through a projection on bar 42 and is threaded into block 41. Thus, by turning hand screw 45, stationary guide member 22 may be adjusted in position so as to tighten or loosen belt 11. The amount of stretch given to belt 11 determines its paste-carrying capacity. The belt, as previously stated, is a closely wound helix, that is, the adjacent convolutions lie in contact with one another when the belt is not under tension. Stretching of the belt, however, separates the adjacent turns of the helix and increases the size of the capillary spaces 39 so that a larger amount of paste is carried by the belt and applied to the surface of the label in much the same manner as spreading of the nibs of a writing pen increases the flow of ink from the pen to the paper.

The guiding stud 23 and the positioning shoe 24 serve to cause the belt 11 to make proper contact with the surface of the uppermost label in stack 8. It is important that the belt be prevented from touching the upper right-hand corner of the stack of labels, as shown in Figs. 4, 1 and 3, as it approaches the label surface, since contact of the belt with any sharp surface would cause the removal of a large quantity of paste from the belt. Hence, if the belt were allowed to slide over the corner of the label stack 8, a large amount of paste would be deposited on the vertical side of the label stack and this would run down the side of the stack, smearing the labels and sticking them together so that their appearance would be injured and the removal of the labels one at a time from the top of the stack would be interfered with.

The upper surface of guiding stud 23 is positioned above the stack of labels and also above the guiding surface 46 of shoe 24. The elevation of guiding stud 23 and the pressure of shoe 24 compel the belt 11 to approach the surface of the label from a point above the label as shown in Figs. 4 and 1, and the forward end of guiding surface 46 is positioned from about $3\frac{1}{2}$ " to $4\frac{1}{2}$ " to the left of the edge of the labels. Also, guiding shoe 24 is provided with a pair of feet 47 which straddle the belt 11 and slightly depress the corner of the label stack, as may be seen in

Fig. 4. In this manner the contact of the belt with the corner of the label stack is prevented, and at the same time paste is applied to the label at a point very close to the side edge of the label.

Guiding stud 23 and shoe 24 should always be held in the same relative position, and to maintain them thus they are carried upon a single mounting member 48, a bottom view of which is shown in Fig. 7. Member 48 is pivoted upon a U-shaped bracket 49 (see Fig. 5) by means of a shaft 50 which turns loosely in the bracket and is fixed to member 48 by means of a set screw 51. These parts are held in their assembled relation by collar 52 on the right-hand end of shaft 50 shown in Fig. 3. Also mounted upon shaft 50 is a short arm 53. A helical spring 54 is attached at its upper end to this arm and at its lower end to the center portion of bracket 49.

Arm 53 is made fast to shaft 50 by means of a thumb screw 55 and hence spring 54 serves to urge shoe 24 against the upper surface of belt 11 and provides the proper amount of wiping or rubbing pressure between the belt and the surface of the label. This pressure can be adjusted as desired by means of the thumb screw 55. Bracket 49 is supported upon bar 42 on which it is slidably mounted and may be adjusted in its position by thumb screw 56. By this lateral adjustment of bracket 49 the feet 47 of shoe 24 are made to engage the surface of the uppermost label in close proximity to the corner of the label stack 8.

When the natural shape of the upper surface of the labels in the stack is straight or convex from side to side, the arm 53 is adjusted to a position adjacent the left-hand edge of the label stack as viewed in Figs. 1 and 3, in order to insure that the spring touches and applies paste to the left-hand edge of the label as it passes off of the same. When, however, the upper surface of the labels is concave arm 53 is shifted to the center of the label stack and in this position, as shown in Fig. 4, it forces the surface of the belt 11 downward into contact with the depressed center of the label.

To permit this adjustment arm 53 is mounted near the end of a transversely disposed rod 57 (Fig. 3). This rod is slidably and rotatably mounted in a projection 58 that extends vertically from bracket 17a, previously referred to. On the outer end of rod 57 there is a short arm 59, which is shown in dotted lines in Fig. 2, and to the outer end of which a biasing spring 60 is attached. By means of this spring arm 53 is urged downwardly against the surface of belt 11 and maintains the portion of the belt to the left of shoe 24 in contact with the surface of the label. Arm 59 is held upon rod 57 by means of a set screw shown in Fig. 2. When arm 53 is shifted from the middle of the label to a position near the edge of it, the screw in arm 59 may be loosened so as to permit the arm to be shifted correspondingly on rod 57.

The stack of labels 8 is supported upon a platform 61 within a cage formed by vertical bars 65 which depend from a pair of frame members that extend horizontally along each side of and near the top of the label stack. The inner surfaces of vertical bars 65 and the frame members 66 serve to keep the labels in alignment. Platform 61 is vertically adjustable to accommodate stacks of different heights and is provided with yielding means such as a spring for exerting a gentle upward push upon the label stack against the pressure of belt 11 and guiding shoe 24, there-

by feeding the stack upwardly as the labels are removed and maintaining the uppermost label in contact with the belt.

The brackets 17a and 17b referred to previously and shown in Figs. 3, 2 and 8 are mounted upon web-like horizontal extensions 67 which are provided along the lower edges of frame members 66. These brackets are frictionally held in position upon web-like members 67 by means of wide flat springs 68 that are attached to the bottoms of the brackets and engage the lower surfaces of the web-like members as shown clearly in Fig. 8. As previously described, each of brackets 17a and 17b has an obliquely extending arm 17 which affords pivoted support for the curling bar 12. They also each have long horizontal arms 69 which may be seen in Figs. 3 and 2 to the ends of which springs 18 are attached which yieldingly urge the curling bar against the uppermost label. Brackets 17a and 17b are alike except for the fact that bracket 17a is provided with a vertical projection 58 for supporting rod 57 and arm 25. Projection 58 also serves another function which will now be described.

It will be observed from Figs. 1, 2 and 8 that the upper part of the label stack 8 consisting of some half dozen labels projects above the tops of frame members 66. This is necessary in order to insure that the uppermost label will be picked up by the approaching can since a stack of labels is easily compressible, and must be compressed somewhat in order to provide sufficient pressure between the can and the uppermost label to insure that they will adhere to each other. If the upper portion of the label stack did not extend above the tops of members 66 the approaching can would be supported by these members and insufficient pressure would be exerted between the uppermost label and the can to cause it to adhere to the can without fail.

One of the difficulties heretofore encountered with the wide flat belts of rubber, leather, etc. heretofore used has been that the great amount of friction between such a belt and the uppermost label caused the lap end of the label to be swept to one side of the stack. It was a difficult problem to support the stack in such a way as to cause the front end of the label to be with certainty picked up by the can and to prevent the rear end of the label from being moved to one side by the belt.

With the employment of the helically wound metal wire belt of my present invention, however, the friction between the belt and the label is so small that it is ordinarily less than the friction between the uppermost label and the label next to it so that no sidewise displacement of the label occurs. However, to positively prevent such sidewise displacement it is only necessary to provide a stop for the side edge of the uppermost label adjacent the belt 11. This stop as shown in Figs. 2 and 8 consists of the upper part of projection 58 on bracket 17a which extends above the upper surface of frame members 66. Preferably the upper portion of extension 58 is provided with an extension 70 (Figs. 2 and 3) which extends to a point close to the belt 11.

Projection 58 and its extension 70 are the only parts which contact with and afford any sidewise support to the labels which are above the tops of frame members 66. With the upper portion of the label stack left unsupported in the sidewise direction except in the manner just described, the operation of the paste-applying mechanism with a wide flat belt as heretofore

employed would be extremely difficult, if not quite impossible. It has been found unexpectedly, however, that with the belt made of a metal wire helix above described, there is no tendency for the shifting of the label to occur.

Paste is prevented from accumulating in the groove of pulley 19 by means of a resilient scraping finger 62, the end of which is shaped to conform to the surface of the pulley. This finger consists of a thin strip of metal having its right-hand portions, as viewed in Figs. 1 and 3, so shaped that it may be conveniently supported upon the side of bracket 43 by means of a pair of screws 63. This scraper is mounted so as to engage the surface of pulley 19 at the point where belt 11 leaves the pulley. The belt, in fact, rides lightly in contact with the upper surface of this scraper and in this way any paste which the belt may tend to leave in the groove of pulley 19 is immediately scraped from the groove and the belt picks it up again from the upper surface of scraper 62.

The ends of the helically wound belt 11 are secured together by means of a short section of similarly wound spring 64 shown in Fig. 4. This short section is of a diameter to fit within the interior of belt 11 and its convolutions have the same pitch so that the two ends of the belt may be threaded one upon each half of the section 64, bringing the ends of the belt into such close proximity that it is difficult to locate the joint in the belt.

The diameter of belt 11 is chosen to deposit a strip of paste of the desired width across the ends of the labels. In the labeling machines 35 which I have thus far equipped with the improved paste-applying device of my present invention, I have used helical belts of $\frac{1}{8}$ " external diameter, and such a belt deposits upon the labels a strip of paste about $\frac{1}{8}$ " in width.

By means of the improved paste-applying mechanism of my present invention, the paste is placed upon the lap end of the label in a continuous line or strip running across the end of the label commencing at a point very close to one side edge of the label and extending all the way to the opposite edge of the label. The application of the paste close to the right-hand edge of the label can be very accurately controlled by adjusting the position of the shoe 24 without fear of having paste run down the edge of the stack of labels. The desired amount of paste to produce a neat application of the label to the can can be very easily and quickly controlled or regulated by varying the tension on the belt 11 55 even while the labeling machine continues in operation.

If it is necessary to stop the labeling machine from any cause, it is not necessary to raise the belt 11 from contact with the stack of labels. 60 While during such a period an excess of paste may flow from the belt onto the surface of the label, as soon as the machine is again started this surplus paste is promptly picked up by the belt and returned to paste receptacle 20. Only 65 a few revolutions of the belt are required to do this. After the machine has been shut down for the night, however, it is desirable each morning to wash the belt free from the paste which has become caked upon it during the night. This may 70 be very readily done, however, without separating the ends of the belt at the ends of the joining section 64. It is only necessary to slip the belt off from the guide 22 and free it from the guide 23 and shoe 24. The belt can then be freed 75

from pulley 19 and entirely removed from the machine merely by elevating the wiping device 29.

On account of the extremely small amount of friction between the surface of the metal spring 5 belt and the surface of the label, the labels can be readily retained in the stack without tendency to pull the stack to one side.

The speed at which the belt 11 is operated depends upon the rapidity with which the labels 10 are removed from the stack 8 and applied to the cans. Thus, when the rate of application of the labels is relatively low, the speed of the belt may be low, and vice versa. The speed of the belt, however, must be sufficiently high that a given 15 point of the belt will travel a distance equal to the width of the labels in the period of time which elapses between the removal of successive labels. Otherwise the strip of adhesive will not extend all the way across the label, since a portion 20 of the label would be wiped only by a portion of the belt from which paste had already been removed by the previous label.

It is to be understood that the above is merely an exemplifying disclosure and that changes may 25 be made in the construction of the device which are within the terms of the appended claims without departing from the scope of the invention.

I claim:

30 1. In an adhesive-applying mechanism, an adhesive-applying member of helical form, means for applying a surplus of adhesive to said member, means for removing therefrom all said adhesive except that retained by capillarity within the 35 spaces between the convolutions of said member, means for moving said member in contact with the surface to which the adhesive is to be applied, and means for varying the spacing of said convolutions to control the amount of adhesive applied by said 40 member.

45 2. In an adhesive-applying mechanism, an adhesive-applying member comprising a resilient filamentary body wound into the form of a closely-coiled helix, means for applying a surplus of adhesive to said member, means for removing therefrom all said adhesive except that retained by capillarity within the spaces between the convolutions of said member, means for moving said member in contact with the surface to which the 50 adhesive is to be applied, and means for stretching said member so as to increase the spacing of said convolutions and thereby increase the amount of adhesive applied by said member.

55 3. In an adhesive-applying mechanism, an endless belt consisting of a helix of resilient metal wire, means for applying a surplus of adhesive to the belt, means for removing therefrom all said adhesive except that retained by capillarity within the spaces between the convolutions of said belt, 60 means for wiping the belt over the surface to which the adhesive is to be applied, and means for stretching the belt to increase its adhesive-carrying capacity.

4. In an adhesive-applying mechanism, an adhesive-applying member comprising an endless belt of resilient filamentary material wound in helical form, and a support for said member having a stationary surface over which the belt slides, and means for preventing the collection of adhesive on said support comprising a stationary curved surface for leading the belt onto said support and a second stationary curved surface for discharging the belt from said support. 10

5. In an adhesive applying mechanism, an adhesive-applying member comprising an endless belt of resilient filamentary material wound in helical form, and means for supporting and changing the direction of travel of the belt comprising a hub member having a plurality of spaced radial fingers projecting therefrom each of said fingers having a saddle-shaped seat for preventing the sidewise displacement of the belt, and being curved in the direction of travel of the belt, the 15 radii of curvature thereof being greater than the radius of curvature of the belt. 20

6. In an adhesive-applying mechanism, an endless belt consisting of a helix of resilient metal wire for carrying the adhesive, and a support for 25 said belt serving as a pulley and comprising a stationary hub member having a plurality of spaced radial fingers projecting therefrom, each of said fingers having a stationary curved surface over which the belt slides, and means on each of said 30 fingers for preventing the collection of adhesive comprising a stationary curved surface for leading the belt onto said finger and a second stationary curved surface for discharging the belt from said finger. 35

7. In an adhesive-applying mechanism, an adhesive-applying member, said member having adhesive-carrying capillary pockets the capacity of which can be varied, means for loading said member with adhesive, means for removing all said adhesive except that retained by capillarity within said pockets, means for causing said member to wipe against the surface to which the adhesive is to be applied, and means for controlling the size of said pockets to regulate the amount of adhesive deposited on said surface. 40 45

8. In a labelling machine means for supporting a stack of labels with their inside surfaces turned upwardly, means for withdrawing the uppermost label from the stack and applying it to an article, a belt having one reach thereof arranged to travel over the surface of said uppermost label, said belt having adhesive-carrying pockets of adjustable capacity, means for loading said belt with adhesive, means for removing all said adhesive except that retained by capillarity within said pockets, the latter adhesive being deposited upon the surface of said uppermost label in a narrow film-like band, and means for varying the capacity of said pockets to regulate the amount of adhesive deposited on said film-like band. 50 55 60

WALLACE D. KIMBALL.
